LOOM SHUTTLE

John J. Kaufmann, Jr., Greenville, S. C., assignor to Steel Heddle Manufacturing Co., Philadelphia, Pa., a corporation of Pennsylvania

Application June 24, 1940, Serial No. 342,014

4 Claims. (Cl. 139—208)

This invention relates to loom shuttles, and it relates more particularly to improved means, in such shuttles, for holding the bobbin against longitudinal displacement on the spindle.

Heretofore various means have been suggested for preventing undesired movement of the bobbin on the spindle, but none of these have proved entirely satisfactory.

The principal object of the present invention is to provide, in a loom shuttle, simple, efficient and inexpensive means for holding the bobbin against longitudinal movement on the spindle after the bobbin has been placed on the spindle, and when it is in its operative position.

A further object of the invention is to provide a device of the character aforesaid which will permit the ready placing and removal of the bobbin with respect to the spindle, without likelihood of damage to any of the parts.

A further object of the invention is to provide a device of the character aforesaid which will readily accommodate itself to slight variations in size and location of the bobbin, and which will serve to reduce wear on the parts to a minimum.

The nature and characteristic features of the invention will be more readily understood from the following description, taken in connection with the accompanying drawing forming part hereof, in which:

Figure 1 is a top or plan view of a loom shuttle provided with a bobbin holding device embodying the main features of the present invention;

Fig. 2 is a longitudinal sectional view thereof, with the spindle and bobbin in the raised or doffing position;

Fig. 3 is a transverse sectional view taken on the line 3—3 of Fig. 1;

Fig. 4 is a similar section taken on the line 4—4 of Fig. 1; and

Fig. 5 is a perspective view of the bobbin holding member detached from the shuttle.

It should, of course, be understood that the description and drawing herein are illustrative merely, and that various changes and modifications may be made in the structure disclosed without departing from the spirit of the invention.

Referring to the drawing, 10 is a shuttle body of a usual type, provided with a spindle opening 11, and having a spindle 12, the heel 13 of which is pivotally supported by a bolt or pin 14. The heel 13 of the spindle 12 is provided with the usual flat side 15, and projection 16, adapted to be engaged by one end of a plate spring 17, which

serves to retain the spindle 12 either in its normal axial position within the shuttle 10, or in its upturned or doffing position as shown in Fig. 2 of the drawing. The plate spring 17 is secured in place in the shuttle 10 by means of the usual bolt or screw 18.

The bobbin 19 is adapted to be positioned upon, or removed from, the spindle 12 in the usual manner. The bobbin 19 is usually formed of a relatively light material, such as paper or the like, and preferably is provided at its rear end with a thin metal ferrule 20 terminating in a flange 21.

The bobbin holding member 22, illustrated in detached perspective in Fig. 5 of the drawing, is preferably made of rubber or other similar resilient material, and it is suitably positioned within the shuttle body 10 so that it may properly function in the manner to be hereinafter set forth.

The bobbin holding member 22 preferably comprises a block having a channel 23 at its front, through which channel 23 the ferrule portion of the bobbin 19 extends, when the spindle and bobbin are in their operative positions within the shuttle body 10.

To the rear of the channelled front portion of the member 22, there is provided an internal vertical recess 24, on each side and at the bottom, which recess 24 is adapted to receive the flange 21 of the ferrule portion of the bobbin 19. The recess 24 is flared at the top, as at 25, to facilitate the insertion of the flange portion 21 of the bobbin 19 in said recess 24.

At the rear of the block 22 there is also provided a channel 26 through which the heel 13 of the spindle 12 extends, and in which it is seated when the spindle 12 is in the operative position within the shuttle body.

The resilient block member 22 is preferably mounted in horizontal recesses 27 in the side walls of the shuttle body, which recesses 27 extend inwardly from the spindle opening 11.

A transverse pin 28 extends through the shuttle body and through an aperture 29 in the block member 22. The pin 28 serves to maintain the block member 22 in its proper position within the recesses 27.

The operation of placing the wound bobbin on the spindle, or removing the empty bobbin therefrom, is precisely the same as in the ordinary form of shuttle which is not provided with the present form of holding device.

It will be noted that the holding device constructed and arranged as hereinabove set forth,

will readily accommodate itself to slight inequalities of size and location of the flanged end of the bobbin, and wear on the parts will be reduced to a minimum.

Furthermore, the use of a resilient material, such as rubber, for the holding device, serves to dampen undesired vibration of the spindle and its associated parts, thereby also assisting in eliminating wear on such parts.

The wear on the block member 22 being practically nil, the proper axial alinement of the spindle, in its operative position, may thereby be maintained over a long period of use.

I claim:

1. In a loom shuttle having a pivotally mounted spindle member for supporting a bobbin in normal operating position within the shuttle and which may be moved to doffing position relative thereto, the means for holding the bobbin against longitudinal movement on the spindle comprising a block member mounted in the shuttle body, said block member being made of resilient material and having an internal recess flaring at the top and adapted to receive the flange of the bobbin, said block also having a channel in its front portion through which the bobbin extends and a channel in its rear portion through which the heel of the spindle extends.

2. In a loom shuttle having a pivotally mounted spindle member for supporting a bobbin in normal operating position within the shuttle and which may be moved to doffing position relative thereto, the means for holding the bobbin against longitudinal movement on the spindle comprising

a block member made of resilient material and having an internal recess adapted to receive the flange of the bobbin, said block also having a channel in its front portion through which the bobbin extends and a channel in its rear portion through which the heel of the spindle extends, and means for maintaining said block member in fixed position in the shuttle body.

3. In a loom shuttle having a pivotally mounted spindle member for supporting a bobbin in normal operating position within the shuttle and which may be moved to doffing position relative thereto, the means for holding the bobbin against longitudinal movement on the spindle comprising a block member made of resilient material and having an internal recess flaring at the top and adapted to receive the flange of the bobbin, said block also having a channel in its front portion through which the bobbin extends and a channel in its rear portion through which the heel of the spindle extends, said block member being seated in longitudinal recesses in the side walls of the shuttle body, and a pin extending through the shuttle body and said block member for maintaining said block member in position.

4. In a loom shuttle in which a flanged bobbin is supported in normal operative position, the means for holding the bobbin against longitudinal movement within the shuttle comprising a rubber block member fixedly positioned in the shuttle body and having an internal recess in which the flange of the bobbin is seated in its operative position.
